UNITED STATES PATENT OFFICE

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

LOOSE-LEAF BINDER

Application filed June 16, 1927. Serial No. 199,199.

This invention relates to loose leaf binders of the book type having mating prongs or half rings which engage the perforated margins of the leaves. It is customary to make these prongs or hooks with a spring mounting so that they snap together when closed, and when opened are held by spring pressure against closing. One customary construction is to mount the half rings or hooks on separate hook plates which have a rocking engagement at their inner edges reacting outwardly against the inturned flanges of a bowed spring plate. Such loose leaf mechanism is commonly applied to the book cover by means of an outer binding plate having prongs or ears passing through the back of the cover and clinched down upon the spring back plate or upon a binding plate interposed between such spring plate and the inner face of the back of the cover.

The present invention relates to improved details of construction, including means for operating the hook plates in order to open or close the rings. It also relates to the fastening means for connecting the loose leaf binding mechanism to the cover back. In the accompanying drawings, which illustrate a suitable embodiment of the invention:

Figure 1 is an end elevation of a fragment of a loose leaf ring back, the cover sides being broken away.

Fig. 2 is a similar view in transverse section on the line 2—2 of Fig. 3.

Fig. 3 is a plan partly broken away in section of the binding mechanism.

Fig. 4 is a longitudinal mid-section on the line 4—4 in Fig. 1.

Fig. 5 is a plan of the outer back portion of the book.

Fig. 6 shows the punching from which the skeletonized outer binding plate is formed.

Fig. 7 is a transverse section of this binding plate after being pressed into shape, with its fastening ears turned up.

Fig. 8 is a plan of the back plate.

Fig. 9 is a plan of the spring plate.

Fig. 10 is a perspective view of one of the

ring-opening levers in its relation with the hook plate.

Fig. 11 is a similar view showing one of the ring-closing levers.

Referring to the drawings, A designates as a whole the loose leaf binding mechanism, and B the book cover. The mechanism A may be of any suitable type, being shown as composed of half rings or hooks *a*, *a* mounted on hook plates *b*, *b* which have a rocking engagement at their inner or adjacent edges, and at their outer edges are supported in the inturned hooked flanges of a spring plate *c*. A cover plate *d* covers over the top of the plates *b*, *b* and makes an attractive finish.

The cover B is shown as formed of a single piece of leather or similar material, being preferably formed with longitudinal grooves *e*, *e* at each side of its rounded back portion for affording a flexible hinge connection between the sides and back of the cover, as is usual.

For fastening the binding mechanism A to the cover, an outer back plate or binding plate C is provided. This has ears *f*, *f* projecting from it at intervals, these ears being passed through holes in the leather and clinched down upon the edges of an inner back plate D whereby to clamp the back portion of the cover firmly between these plates. The plates are preferably made curved in cross-section so as to give the desirable rounded form to the book back. The inner back plate D has on its ends, ears *g*, *g* which are turned up, entering notches *h*, *h* formed in the ends of the spring plate *c* and are clinched down upon the top of the spring plate so as to hold the latter, and consequently the entire loose leaf binder mechanism securely in place with respect to the cover.

The outer binding plate C is of novel construction. With certain books it is desirable to form cross-bars on the book back at intervals; and for this purpose metal cross-pieces or hubs have been provided having projecting ears which are passed through the middle of the back and clinched down upon the inner face of the leather. These hubs have sometimes been sunken into recesses of the

outer face of the leather back so as not to project beyond the leather. Such hubs have to be separately applied to the book back, which is laborious. The present invention provides for connecting the cross-pieces or hubs together by forming them in one plate or punching, as shown in Fig. 6. This plate C has transverse bands or hub portions *i*, *i* at intervals connected by a longitudinal strip *j*. With the plate thus blanked out it is only necessary, when the ears *f* have been turned up at right angles and when the cover has had corresponding holes pierced through it to receive these ears, to apply the one plate to the cover back, inserting its ears through such holes and then apply the inner back plate D against the inner face of the cover back to clinch the ears *f*, *f* down so as to embrace the marginal portions of the plate D entering notches *k*, *k* therein. The spring plate has a series of openings *c*' coinciding with the bent ears *f* and which may be entered by the latter to make the metal parts lie as close together as possible.

It is desirable to sink the strip *j* into the leather as well as the cross-bars *i*, *i*.

It is desirable in such ring books to provide means for conveniently springing the hooks apart and pressing them together. For this purpose opening and closing levers have been provided. According to the present invention the opening levers consist of crossed metal arms F, F, shown best in Fig. 1, and one of which is shown in Fig. 10. These arms are punched from sheet metal, the plane of which is transverse to the direction of the several plates, including the hook plates *b*, *b*. Each arm F is formed with an elongated slot *p* and the end of the hook plate is cut out to form a flat projection or tenon *q* which enters the slot *p*. The two plates F, F pass upwardly through a slot *r* in the cover plate *d* near its end, as shown in Figs. 3 and 4, and this slot serves to hold the plates in their proper planes and prevents them from becoming disengaged from the hook plates *b*. The arms F are preferably turned laterally at *s* so as to form finger pieces which may be grasped and pressed together in order to open the hooks or rings.

The closing plates G, G are shown best in Fig. 2, one of them being shown in Fig. 11. They are similar to the plates F, F except that they do not cross each other but project directly upward so that both may work in one slot *t* in the opposite end of the cover plate *d*. Each arm G is formed with a slot *p'* and each plate *b* is formed with a projection or tenon *q'* (Fig. 11) which enters the slot *p'*, so that when the hooks are open, the pressing together of the arms G, G tilts the hook plates and closes the hooks. These parts are readily assembled and are held in their proper position by the cover plate when this is slipped over the spring plate. The arms G, G are

desirably turned back at *s'* to form finger pieces.

The entire construction shown makes a very simple and easily made and assembled binder of desirable operation, and one which is durable and effective.

The invention may be modified to some extent within the scope of the appended claims.

What I claim is:

1. A loose-leaf book comprising a binding mechanism and a cover, the latter formed of one piece of leather-like material, and a skeletonized metal back-plate applied to the exterior of the cover back and having means passing through the cover for fastening the binding mechanism to the cover.

2. A loose-leaf book comprising a binding mechanism and a cover, the latter formed of one piece of leather-like material, and a skeletonized metal back-plate applied to the exterior of the cover back to present a composite outer back surface of cover material and metal.

3. A loose-leaf book comprising a binding mechanism and a cover, the latter formed of one piece of leather-like material, and a skeletonized metal back-plate applied to the exterior of the cover back comprising cross-bars of metal united by a longitudinal portion, whereby all are handled as one unit in applying to the book-back.

4. A loose-leaf book comprising a binding mechanism and a cover, with a metal binding-plate on the outer back of the cover and a back plate on the inner side of the cover back, the binding-plate having lateral ears passing through the cover and clinching on the sides of the back-plate, and the binding mechanism including a spring-plate fastened to the back-plate and having openings coinciding with such clinched ears to admit the latter and enable the spring-plate to closely overlie the back-plate.

5. A loose-leaf book comprising a binding mechanism having hook-plates carrying mating hooks, and operating means therefor comprising a pair of arms united to the ends of said plates at one end of the book-back and projecting into position to be moved toward each other to tilt the plates and operate the hooks.

6. A book according to claim 5, the arms lying in planes transverse to said plates, and having slots and the hook-plates having projections entering such slots to unite the plates and arms.

7. A book according to claim 5, the arms being in planes transverse to said plates, with a cover-plate overlying the hook-plates, having transverse slots for the passage of the operating arms.

8. A book according to claim 5, with a cover-plate overlying the hook-plates, having transverse slots for the passage of the oper-

ating arms, adapted to guide said arms in their movements.

5 9. A book according to claim 5, the arms being in planes transverse to the plates and having slots and the hook-plates having projections entering such slots to unite the plates and arms, and with a cover-plate overlying the hook-plates, having transverse slots for the passage of the arms, whereby the arms 10 are held in engagement with the projections on the plates.

15 10. A loose-leaf book comprising a binding mechanism and a cover with spaced transverse cross-pieces of metal applied at intervals on the outer back of the cover and sunk into the material thereof, each having ears projecting beyond its ends at the sides of the book back, bent up, passing through the cover and clinched down internally thereof.

20 11. A loose-leaf book comprising a binding mechanism and a cover with transverse cross-pieces of metal applied at intervals on the outer back of the cover and sunk into the material thereof, each having ears projecting beyond its ends at the sides of the book back, bent up, and passing through the cover, and a 25 plate on the inner side of the cover, said ears clinched down against the side edges of said plate.

30 In witness whereof, I have hereunto signed my name.

CLARENCE D. TRUSSELL.
